LIFE-PRESERVING BATHING SUIT

James M. Combs, Cleveland, Ohio

Application March 30, 1945, Serial No. 585,699

10 Claims. (Cl. 9—20)

1

This invention relates, as indicated, to a life-preserving bathing suit.

A primary object of the invention is to provide a bathing suit of the character described, which is especially adapted to be worn by children, and which is highly effective to sustain a child's body afloat for a considerable time, even in the event of injury or damage to portions of the suit.

Another object of the invention is to provide a bathing suit of the character described having a novel arrangement of distensible pouches and a manifold tube for simultaneously admitting air into all of the pouches.

A further object of the invention is to provide a bathing suit of the character described in which air-tight joints between the manifold tube and the distensible pouches are obtained by means of coupling elements of efficient and durable construction, which may be easily attached or removed for replacement purposes.

A still further object of the invention is to provide a bathing suit of the character described which is extremely neat and attractive in appearance, free from bulkiness, and extremely light in weight.

Other objects and advantages of the invention will be apparent during the course of the following description.

In the accompanying drawings, forming a part of this specification, and in which like numerals are employed to designate like parts throughout the same,

Fig. 1 is a front elevational view of a child's bathing suit embodying the invention;

Fig. 2 is a fragmentary cross-sectional view of a portion of the front of the suit, taken on the line 2—2 of Fig. 1;

Fig. 3 is a top plan view of the tube and pouch unit, as viewed in the direction indicated by the arrows 3—3 of Fig. 1;

Fig. 4 is an exploded view of the elements of parts used for connecting each of the rubber pouches to the manifold tube, and

Fig. 5 is a view of the parts shown in Fig. 4, but in fully assembled relation.

Referring more particularly to the drawings, wherein is shown, for purpose of illustration, a child's bathing suit, the bathing suit will be seen to comprise a body portion 1, consisting of a front and back, shoulder straps 2, and leg or thigh portions 3, the suit being made of any suitable textile or knitted fabric, as is customary in the manufacture of such bathing suits.

Secured to the inner faces of the front and back portion 1 of the suit, as by parallel horizon-

2

tal lines of stitching 4 and 5, is an annular band 6 of a fabric similar to that from which the suit as a whole is made. This band is further secured to the front and back portions 1 of the suit by parallel vertical lines 7 of stitching, which provide between such lines of stitching a series of vertically-disposed pockets 8, which are closed at the bottom by the stitching 5, and are partially closed at the top by the stitching 4.

10 The stitching 4 is interrupted at points intermediate the points of intersection of the stitching 4 and stitching 1 to provide openings through which pouches or containers 9 of rubber or like distendable material may be introduced into the 15 pockets 8, as clearly shown in Fig. 1. These pouches or containers are preferably similar in size and contour to the conventional type of prophylactic sheath, but are of somewhat greater wall thickness than the latter. These pouches, 20 moreover, have a somewhat contracted neck portion 10, the function of which will hereinafter appear.

The portion of the fabric band 6, which is disposed above the line of stitching 4 forms a loose 25 flap 11 (Fig. 2), which is provided adjacent its upper edge with a series of spaced snap fasteners 12, which may be removably secured to cooperating snap fasteners 13 on the inner face of the body portion 1 of the suit. The flap 11, when secured to the body 1 of the suit, as in Fig. 2, forms 30 an annular pocket or compartment 14 in which is disposed a soft flexible tube 15 of rubber or the like, which is closed at one end, as at 16, and has secured to its other end a valve 17, through which 35 air may be blown, when a valve closure 18 is unscrewed.

The tube 15 forms a manifold for supplying air to each of the pouches or containers 9, when air is blown through the valve 17.

40 An important feature of the invention resides in the means whereby the tube or manifold 15 is connected to each of the pouches or containers 9. For this purpose, as best shown in Figs. 4 and 5, the tube 15 is provided in its wall with perforations 19, which are spaced to correspond with the spacing of the necks 10 of the pouches 9. These perforations 19 form openings through which the externally threaded shank 20 of a connector element 21 may be passed, as in Fig. 5, the perforation 19 being of somewhat smaller diameter than the diameter of the shank 20, so that the tube will securely hug the shank. The connector element 21 is provided with an axial port or opening 22, forming a passageway for the passage of 45 air from the tube 15 to the interior of the pouch 9.

The connector element 21 is rigidly secured to the tube 15 by means of a nut 23, which is threadedly secured to the shank 20, and which, when drawn up to the position shown in Fig. 5, clamps the wall of the tube about the opening 19 between the upper flat face of a washer 24, which is interposed between the tube and the nut 23, and the lower flat face of the head of the element 21. The nut 23 is provided with a convex or spherical upper face 25.

The washer 24 has a convex or spherical lower face 26, which, when the nut 23 is drawn up into abutment with the washer, as in Fig. 5, is disposed opposite the face 25 of the nut 23, the faces 25 and 26 forming an annular recess therebetween of wedge-shaped cross-section.

In connecting each of the pouches 9 to the tube 15, the parts 21, 23 and 24 are first assembled with the tube as in Fig. 5, after which the constricted neck 10 of the pouch 9 is placed opposite the annular recess formed by the faces 25 and 26 respectively. Then, by means of a rubber band, string, or thread, indicated at 27 in Fig. 5, the neck 10 is drawn up into the recess, and tied to the nuts 23 and washer 24. The faces 25 and 26 exert a wedge-like pressure on the portion of the neck 10 which is thus drawn into the aforesaid annular recess, and this has been found highly effective in forming a tight, waterproof and air-proof joint between the pouch 10 and the tube 15.

The provision of this coupling or connection between the tube 15 and pouch 10 makes the article, as a whole, a commercially feasible one, since the lack of such a coupling or connection has heretofore been the principal deterrent to the production of this otherwise highly desirable item of wearing apparel.

The use of the garment will be readily understood from the foregoing description.

The garment is first placed on the child in the ordinary manner, and with the pouches 9 in deflated condition. The pouches may then be filled with air either by the child, or by an adult, who will blow air through the valve 17 and into the tube 15 until the pouches 9 are properly inflated. The valve 17 is readily accessible for this purpose, since a considerable portion of the tube projects through an opening 28 in the suit, which opening is disposed behind a pocket 29 on the front of the suit. When the pouches have been properly inflated, the valve 17 is closed, and the projecting portion of the tube 15 may be folded and placed inside the pocket 29.

Should one or several of the pouches 9 become punctured, the leakage from the remaining pouches into and through the punctured pouch or pouches will be at such a slow rate, that the child will be maintained afloat for a considerable period.

Although a series of pouches is shown as disposed at both the front and back of the body portion of the bathing suit, it will be readily understood that either the front or back series may be eliminated, since sufficient buoyancy will be afforded by a single series of such pouches, when properly inflated.

It is to be understood that the form of my invention, herein described, is to be taken as a preferred example of the same, and that various changes may be resorted to without departing from the spirit of my invention, or the scope of the subjoined claims.

Having thus described my invention, I claim:

1. In a bathing garment, a series of parallel pockets, pouches of a distensible material disposed in said pockets, a manifold tube of flexible material disposed adjacent said pouches, and means connecting said manifold tube with each of said pouches, said means comprising an element connected to said tube and a flexible attaching element securing the mouth of the pouch to said first-named element.

2. In a bathing garment, a series of parallel pockets, open-ended pouches of a distensible material disposed in said pockets, a manifold tube of flexible material disposed adjacent the openings in said pouches, and means connecting said manifold tube with each of said pouches, said means comprising a connector element rigidly secured to said tube, and a flexible cord-like element securing the open end of said pouch into constricted air-tight relation to said connector element.

3. In a bathing garment, a series of parallel pockets, open-ended pouches of a distensible material disposed in said pockets, a manifold tube of flexible material disposed adjacent the openings in said pouches, and means connecting said manifold tube with each of said pouches, said means comprising a connector element having an axial passageway therethrough communicating the interior of said tube with the interior of the pouch, a nut rigidly securing said connector element to said tube, a washer secured to said connector element, said nut and washer coacting to form an annular recess, and means drawing the open end of said pouch into said recess to form an air-tight joint between said pouch and said nut and washer.

4. In a bathing garment, a series of parallel pockets, open-ended pouches of a distensible material disposed in said pockets, a manifold tube of flexible material disposed adjacent the openings in said pouches, and means connecting said manifold tube with each of said pouches, said means comprising a connector element having a threaded shank and an axial passageway through said shank communicating the interior of said tube with the interior of the pouch, a nut mounted on said shank and rigidly securing the connector element to said tube, a washer mounted on said shank, said nut and washer coacting to form an annular recess therebetween, and means for drawing the open end of said pouch into said recess, thereby constricting the open end of the pouch and establishing an air-tight joint between said pouch and said nut and washer.

5. In a bathing garment, a series of parallel pockets, open-ended pouches of a distensible material disposed in said pockets, a manifold tube of flexible material disposed adjacent the openings in said pouches, and means connecting said manifold tube with each of said pouches, said means comprising a connector element having a threaded shank and an axial passageway through said shank communicating the interior of said tube with the interior of the pouch, a nut mounted on said shank and rigidly securing the connector element to said tube, a washer mounted on said shank, said nut and washer having convex surfaces which coact to form an annular recess of wedge-shaped cross-section, and means drawing the open neck of said pouch into said recess, said last-named means and said convex surfaces exerting a wedge-like pressure on the portion of the neck which is thus drawn into the recess, and forming an air-tight joint between said pouch and said nut and washer.

6. Means for connecting an open-ended rubber pouch to the wall of a flexible rubber tube, said means comprising a connector element having a threaded shank and an axial passageway through said shank communicating the interior of said tube with the interior of said pouch, a nut mounted on said shank and rigidly securing the connector element to said tube, a washer mounted on said shank, said nut and washer coacting to form an annular recess of wedge-shaped cross-section therebetween, and means for drawing the open end of said pouch into said recess to form an air-tight joint between said pouch and said nut and washer.

7. Means for connecting an open-ended rubber pouch to the wall of a flexible tube having an opening in said wall, said means comprising a connector element having a head disposed within said tube and a threaded shank extending through said opening and having a passageway extending through said head and shank adapted to form an air passageway between the interior of said tube and the interior of said pouch, means mounted on said shank and clamping said tube to said head, said last-named means providing an annular recess, and means for drawing a portion of said pouch into said recess to thereby connect said pouch to said clamping means.

8. In a bathing garment, a series of parallel pockets, pouches of a distensible material disposed in said pockets, a single manifold tube of flexible material disposed adjacent said pouches and extending past the mouths of all of the pouches, and means connecting said manifold tube with each of said pouches, said means comprising an element connected to said tube and a flexible attaching element securing the mouth of the pouch to said first-named element.

5 9. In a bathing garment, a series of parallel pockets, pouches of a distensible material disposed in said pockets, a single manifold tube of flexible material disposed adjacent said pouches and extending past the mouths of all of the pouches, and means connecting said manifold tube with each of said pouches, said means comprising a connector element rigidly secured to said tube, and a flexible cord-like element securing the open end of the pouch into constricted air-tight relation to said connector element.

10 15 10. In a bathing garment, a series of parallel pockets, pouches of a distensible material disposed in said pockets, a manifold tube of flexible material disposed adjacent said pouches and having openings in the wall thereof, connector elements having heads disposed in said tube and threaded shanks extending through said openings and having passageways extending through 20 said head and shank adapted to form air passageways between the interior of said tube and the interior of said pouches, means mounted on said shanks and providing annular recesses, the mouths of said pouches being drawn into said 25 recesses and in constricted air-tight relation with said means.
